STARTER BURNER

Anton J. Yeager, Wisconsin Rapids, Wis., assignor to Prentiss Wabers Products Co., Wisconsin Rapids, Wis., a corporation of Wisconsin

Application March 19, 1941, Serial No. 384,039

2 Claims. (Cl. 158—81)

This invention relates to a new and improved starter burner and more particularly to a starter burner for use in connection with blow torches, stoves, heaters or other apparatus using burners operating on liquid hydrocarbon fuel.

With usual types of hydrocarbon burners operating on relatively volatile fuels, such as gasoline or kerosene, the fuel is gasified by heat and burned as gas. During operation of the burner, the liquid fuel is gasified by passing through a generating tube located in heating proximity to the burner flame. In multiple burner stoves, one master burner may supply heat to gasify the fuel for all the burners. In starting up the burner, however, it is necessary to provide means for heating the generating tube to gasify the fuel. Various means have been provided for this purpose, including shallow pans or cups built into the structure to be filled with liquid fuel and lighted to give a flame heating the burner. Other means have been developed, such as starter burners intended to operate on the air under pressure in the upper part of the tank, this air being presumed to contain inflammable vapor from the fuel. These burners are not certain in their operation, since the vapor content of the air is dependent upon the temperature of the fuel and its relative volatility. With fuel of low volatility these burners are ineffective except when the ambient temperature is high.

It is an object of the present invention to provide a new and improved starter burner for burners using light liquid hydrocarbons.

It is a further object to provide a burner of this character which may be instantly lighted with a match or similar small flame.

It is an additional object to provide a construction adapted to effectively atomize and vaporize the liquid fuel by an admixture of air under pressure from the fuel tank.

It is also an object to provide a starter burner construction which is simple in design and use and in which danger of clogging of the orifices is minimized.

Other and further objects will appear as the description proceeds.

I have shown a preferred embodiment of my invention in the accompanying drawing, in which—

Figure 1 is an elevation of a blow torch with my starter burner applied thereto, the blow torch being broken away to show the burner, and the burner being shown in cross-section; and

Figure 2 is a fragmentary cross-section on an

enlarged scale showing the construction of the starter burner.

In the drawing, referring first to Figure 1, the blow torch comprises the tank 11, with the handle 12, and the fuel pipe 13 leading to generator pipe 14, which in turn leads to the generator valve 15. The generator valve is of the usual construction, controlled by hand wheel 16 and discharging the flame into the flame directing hood 17. The blow torch is provided with an air pump 18 operated by plunger knob 19, so that the fuel in the tank 11 is placed under pressure.

The starter burner comprises the body member 21, into the lower end of which is threaded the vapor tube nipple 22 carrying the upper end of the fuel tube 23. The valve stem nipple 24 is secured in the side of the upper portion of the body 21 by brazing or soldering, as indicated at 25, so as to make a permanent and gas-tight joint. The starter body 21 is provided with a central bore 26, which meets a cone-shaped cavity 27 in the lower portion of the body. The upper end of the central bore 26 discharges through a conical end 28 formed on the body. The starter tip member 29 is threaded on the upper part of the body 21, fitting against the cone 28, and is provided with a reduced metering orifice 30 in alignment with the bore 26 in the body. The tip member 29 carries the shield 31 to direct the flame from the starter burner, this shield being provided with air openings 32 as indicated in Figure 1. The body 21 is provided with a conical valve seat 33 which intersects the bore 26 and is adapted to receive the conical end 34 of the valve stem 35, which is threaded into the valve stem nipple 24. This valve stem 35 carries the knob 36 for manual operation. As shown in Figure 1, the nipple 24 carries the gland 37 and packing 38 to prevent gas leakage around the valve stem 35.

The fuel tube nipple 22 is provided with a central bore having a reduced threaded portion at 39, into which the upper end of the fuel tube 23 is threaded. The fuel tube 23 is smaller than the main portion of the bore and the nipple 22, to provide a circumferentially extending passage 40 in communication with the upper portion of the fuel tank. The upper portion of the nipple 22 is conical in shape, as shown at 41, and provides a chamber 42 in communication with the passage 43 in the interior of the fuel tube 23. The conical end 41 is provided with a small central bore through which fuel is directed into the bore 26 in the body member 21. The nipple 22

is provided with lateral openings 44 which communicate between the circumferential chamber 40 around the tube 23 and the chamber 27 between the upper end of the nipple 22 and the body member 21. As shown in Figure 1, the lower end of the fuel tube 23 is provided with a cup-shaped member 45 carrying a screen 46 to prevent entry into the tube of foreign matter which might clog the orifices.

In the operation of the starter burner, it will be understood that the fuel tank is partially filled with liquid fuel, with air under pressure above the liquid fuel. The valve knob 36 is rotated to unseat the conical valve member 34, which permits communication between the fuel tube 23 and the upper portion of the bore 26 in the body 21. When this valve is unseated, liquid fuel flows up through the passage 43 in the fuel tube 23 and through the orifice in the pointed end 41 of nipple 22. This fuel is forced out by air pressure in the tank. At the same time this air under pressure in the tank moves up through the passage 40 through the orifices 44 and through the conical chamber 27 to meet the jet of liquid fuel at the pointed end of the nipple portion 41. This provides, therefore, a conical sheet of air under pressure meeting a small jet of liquid fuel. The air vaporizes the fuel, and the mixture of air and finely divided and vaporized fuel passes up through bore 26 and out through the metering opening 30 in the starter tip member 29. This fuel and air mixture may be ignited by inserting a match through one of the openings 32 in the shield 31. This mixture of atomized and vaporized fuel and of air under pressure produces a hot flame which quickly heats up the generator tube 14. After this tube has had an opportunity to be heated up, the main generator valve 15 is opened by turning the handle 16, and liquid fuel flowing through the valve 15 is vaporized. As soon as the main burner is started, the starter burner is turned off by rotating the valve knob 36. The heat of the main flame during continued operation serves to heat the generator tube 14 and vaporize the fuel as it passes through that tube. The various orifices provided are relatively large for handling such fuel and air and minimize any tendency of clogging. The metering orifice 30 is in the separate tip member 29 which may be readily removed for cleaning or replacement.

While this starter burner has been shown in

connection with a blow torch, it is obviously capable of use in other connections with heaters, stoves or burners of various types. The starter burner may be used with kerosene, gasoline or other similar volatile fuels. The burner structure is capable of modification to meet differing conditions and requirements, and I contemplate such variations as come within the spirit and scope of the appended claims.

What is claimed is:

1. A burner adapted for use in a vessel containing liquid fuel and air under pressure comprising, in combination, a burner body having a central bore therethrough, a vapor tube nipple threaded into said burner body, said nipple having a discharge outlet communicating with said bore, said burner body and said nipple providing an annular passageway therebetween, said nipple also having a bore, a fuel tube located in said bore and threaded into said nipple, said bore providing an annular passageway for air between said fuel tube and said nipple, said nipple having radially directed apertures providing communication between said passageways for directing air under pressure at right angles to said first mentioned annular passageway, the region of said nipple adjacent to its discharge outlet forming with said burner body an annular conical passageway adapted to deliver air from said first mentioned annular passageway into proximity with fuel discharged through said discharge outlet.
2. A burner adapted for use in a vessel containing liquid fuel and air under pressure comprising, in combination, a burner body, a nipple threaded therein, a fuel tube threaded into said nipple, said nipple and said fuel tube providing between them an annular passageway extending throughout a portion of said nipple, said burner body and said nipple providing between them an annular passageway extending throughout another portion of said nipple, said nipple having radially directed passageways connecting said annular passageways for directing air under pressure at right angles to said first mentioned annular passageway, said annular passageway between said burner body and said nipple having at its discharge extremity a conical conformation disposed in position to deliver air coaxially with reference to the discharge of fuel through said fuel tube and nipple.

ANTON J. YEAGER.
